UNITED STATES PATENT OFFICE

111,539

DESIGN FOR A TOILET ARTICLE CASE

George R. Graff, Toledo, Ohio, assignor to The Henkel-Claus Company, Fremont, Ohio, a corporation of Ohio

Application June 16, 1938, Serial No. 77,885

Term of patent 7 years

To all whom it may concern:

Be it known that I, George R. Graff, a citizen of the United States, residing at Toledo, in the county of Lucas and State of Ohio, have invented a new, original, and ornamental Design for a Toilet Article Case, of which the following is a specification, reference being had to the accompanying drawing, forming part thereof.

In the drawing, Fig. 1 is a plan view of a toilet article case, showing the new design.

Fig. 2 is a front elevation of the case.

Fig. 3 is a side elevation of the case.

Fig. 4 is a perspective view of the case with the cover sections in their open positions.

In the drawing the stippling represents pebble leather.

I claim:

The ornamental design for a toilet article case,
as shown and described.

GEORGE R. GRAFF.
